(57) **CLAIM**

The ornamental design for an iris recognition camera, as shown and described.

DESCRIPTION

FIG. 1 is a front view of an iris recognition camera showing our new design;

FIG. 2 is a right side view thereof;

FIG. 3 is a rear view thereof;

FIG. 4 is a left side view thereof;

FIG. 5 is a top plan view thereof; and,

FIG. 6 is a bottom view thereof.

The portions of the article in broken lines are shown for illustrative purposes only and form no part of the claimed design.
